UNITED STATES PATENT OFFICE.

WILLIAM MALLINSON, OF HALIFAX, ENGLAND, ASSIGNOR TO JOSEPH
WILD & CO., OF NEW YORK, N.Y.

DESIGN FOR A CARPET-PATTERN.

Specification forming part of Design No. 5,789, dated April 16, 1872.

Specification describing a new and original Design for a Carpet, invented by WILLIAM MALLINSON, of Halifax, in the county of York, England.

The photographic illustration fully represents my new design.

This invention relates to a new design for a carpet and for the border of the same.

The carpet proper is formed of clusters of leaves set in moss, as shown. The border also consists of clusters of leaves and of narrow outer lines of small figures, as shown.

I claim as my invention—

1. The design for the carpet proper, as shown.
2. The design for the border, as shown.

WILLIAM MALLINSON.
